WOMAN'S STOCKING

Max B. Mueller, Bloomfield, N. J., and Samuel Shapiro, Brooklyn, N. Y.

Application May 18, 1951, Serial No. 15,234

Term of patent 14 years

(Cl. D47—7)

To all whom it may concern:

Be it known that we, Max B. Mueller, a resident of Bloomfield, in the county of Essex and State of New Jersey, and Samuel Shapiro, a resident of Brooklyn, in the county of Kings and State of New York, both citizens of the United States, have invented a new, original, and ornamental Design for a Woman's Stocking, of which the following is a specification, reference being had to the accompanying drawing, forming part thereof.

In the drawing:

Fig. 1 is a side elevational view of the stocking.

Fig. 2 is a fragmentary rear view of the stocking as worn.

I claim:

The ornamental design for a woman's stocking, as shown.

MAX B. MUELLER.
SAMUEL SHAPIRO.
